US00D937100S

(12) **United States Design Patent** (10) **Patent No.:** **US D937,100 S**
Das et al. (45) **Date of Patent:** **** Nov. 30, 2021**

(54) **CONTAINER CARRIER**

(71) Applicant: **World Centric**, Rohnert Park, CA (US)

(72) Inventors: **Aseem Das**, Petaluma, CA (US);
Viktor Jondal, Täby (SE); **Yanghua Ye**, Jiangxi (CN)

(73) Assignee: **World Centric**, Rohnert Park, CA (US)

(**) Term: **15 Years**

(21) Appl. No.: **29/729,789**

(22) Filed: **Mar. 30, 2020**

(51) LOC (13) Cl. **09-03**

(57) **CLAIM**

The ornamental design for a container carrier, as shown and described.

DESCRIPTION

FIG. 1 is a top perspective view of a container carrier showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of a container carrier showing the claimed design;

FIG. 10 is a bottom perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

1 Claim, 10 Drawing Sheets
